(57) CLAIM

The ornamental design for a sun lounger as shown and described.

DESCRIPTION

FIG. 1 is an upper, left, front perspective view of my new design for a sun lounger.

FIG. 2 is an upper, left, rear perspective view thereof.

FIG. 3 is a front elevation view thereof.

FIG. 4 is a rear elevation view thereof.

FIG. 5 is a right elevation view thereof.

FIG. 6 is a left elevation view thereof.

FIG. 7 is a top plan view thereof.

FIG. 8 is a bottom plan view thereof; and,

FIG. 9 is an enlarged detail view taken from the area 9 in FIG. 3.

The dot-dash broken lines are included for the purpose of illustrating the border of the enlarged view in FIG. 9 and form no part of the claimed design. The broken lines shown in the figures are for the purpose of illustrating portions of the sun lounger and form no part of the claimed design. The shade lines shown represent surface shading and not surface ornamentation or material type.
